J. B. DETWEILER.

TOY.

APPLICATION FILED JUNE 24, 1919.

1,318,327.

Patented Oct. 7, 1919.

Inventor

J. B. Detweiler.

A technical drawing of a mechanical device, possibly a valve or actuator, is shown on the left. The drawing includes various parts labeled with numbers: 1, 2, 3, 4, 5, 6, 8, 10, 14, 15, 16, 18, 22, and 23. On the right side of the drawing, there is a large, stylized signature that reads "J. D. Welweiler" at the top and "A. Randolph Jr." below it. Below the signature, the word "Attorney." is written. The entire drawing is on a light-colored background.

UNITED STATES PATENT OFFICE.

JOSHUA B. DETWEILER, OF GOSHEN, INDIANA.

TOY.

1,318,327.

Specification of Letters Patent.

Patented Oct. 7, 1919.

Application filed June 24, 1919. Serial No. 306,298.

To all whom it may concern:

Be it known that I, JOSHUA B. DETWEILER, a citizen of the United States, residing at Goshen, in the county of Elkhart and State 5 of Indiana, have invented certain new and useful Improvements in Toys; and I do hereby declare the following to be a full, clear, and exact description of the invention, such as will enable others skilled in the 10 art to which it appertains to make and use the same.

This invention relates to figure toys, and the primary object of the invention is to provide an improved figure toy mounted 15 upon a wheeled base, so constructed that upon movement of the base the figure will be actuated to cause certain movements.

Another object of the invention is to provide an improved wheeled figure toy including 20 a base having a figure mounted thereon to simulate the appearance of a mule, horse or other quadruped, such figure being operatively connected with the wheels in such manner that upon movement of the device 25 the figure will be actuated so as to elevate the rear portion of the body thereof and lift the legs rearwardly and thus give the appearance of the figure kicking in a life-like manner.

30 A still further object of the invention is to provide an improved wheeled figure toy of the above character, which is durable and efficient in use, one that is simple and easy to manufacture, and one that can be placed 35 upon the market at a reasonable cost.

With these and other objects in view, the invention consists in the novel construction, arrangement and formation of parts, as will be hereinafter more specifically described, 40 claimed and illustrated in the accompanying drawings, forming a part thereof, in which:

Figure 1 is a side elevation of the improved toy,

Fig. 2 is a front elevation of the same, 45 and

Fig. 3 is a top plan view.

Referring to the drawings in detail, wherein similar reference characters designate corresponding parts throughout the several 50 views, the numeral 1 generally indicates the improved toy, which includes a flat substantially rectangular base plate 2 having pairs of bearing brackets 3 and 4 secured to the

lower surface thereof adjacent its forward and rear ends. The forward bearing brackets 5 rotatably support the crank shaft 5 having the forward supporting wheels 6 rigidly secured thereto. The rear axle 7 carrying the rear supporting wheels 8 is journaled in the rear bearing brackets 4. 60

Mounted upon the upper surface of the base plate 2 is a figure 9 formed of a flat piece of metal or other preferred material suitably cut and painted to simulate the appearance of a mule, horse or the like. The 65 figure 9 includes the body 10, the neck 11, head 12, the forward legs 13, and the rear legs 14, which are formed from separate pieces of material as will be hereinafter more fully described. A pivot pin 15 extends through the feet portions of the forward legs 11 and the terminals of the pin are bent downwardly as at 16 and secured to the base plate 2. The pin 15 forms a simple method for pivotally securing the 70 figure 9 to the base plate.

The rear legs 14 are formed from a single piece of material suitably cut and painted and the same are pivotally secured to the rear lower end of the body by a rivet 17. 80 The rivet extends through the upper portion of the legs 14 and is spaced from the upper edge thereof and the forward upper ends of the legs are continued above the pivot pin for a short distance. The feet portions of 85 the rear legs are adapted to rest upon the upper surface of the base plate.

The forward end of the base plate is provided with a longitudinally extending slot 18, through which extends the rod 19, which 90 has its lower end curved to form an eye 19', which receives the crank portion of the shaft 5. The upper end of the rod 19 is bent and passed through an aperture 20 in the lower end of the head 12 of the figure. Thus, 95 when the toy is wheeled over the ground, the figure will be swung on the pivot pin 15.

The extreme upper end of the rear leg 14 is pivotally connected to the rod 21, which has its lower end bent to form an eye 22, 100 which receives the staple 23 which is secured to the base plate forwardly of the rear leg. Thus, when the figure is swung on the pivot pin 15, the rear end of the body will be elevated and the upper terminals of the 105 legs swung downwardly which will raise the

lower ends of the legs rearwardly and in this manner the figure will effectively simulate the appearance of an animal kicking.

In practice, I have found that the form of my invention illustrated in the accompanying drawings and referred to in the above description, as the preferred embodiment, is the most efficient and practical; yet realizing the conditions concurrent with the adoption of my device will necessarily vary, I desire to emphasize that various minor changes in details of construction, proportion and arrangement of parts may be resorted to, when required without sacrificing any of the advantages of my invention as set forth.

What I claim as new is:

1. A figure toy of the class described including a base plate, forward and rear axles carried by the base plate, wheels rigidly secured to the axles, the forward axle having a crank arm formed therein, a figure including a body, head, forward and rear legs, the forward legs being rigidly secured to the body, and means pivotally securing the rear legs to the body, means operatively connecting the crank arm with the forward end of the figure, means pivotally securing the lower terminals of the forward legs to the

base plate, and means connecting the forward upper ends of the rear legs to the base plate, as and for the purpose specified.

2. A figure toy of the class described including a flat base plate, front and rear axles rotatably carried by the base plate, wheels rigidly secured to the axles, the front axle having a crank formed therein, a figure mounted upon the base plate and including forward legs rigidly secured thereto, rear legs pivotally secured thereto, a U-shaped pivot pin extending through the lower terminals of the forward legs and having the terminals of its arms secured to the base plate, said base plate having a longitudinally extending slot formed therein, a connecting rod pivotally secured to the crank and to the lower end of the head of the figure, and a rod having its lower end secured to the base plate and its upper end secured to the rear legs at a point in advance of and above the pivot pin of the rear legs, as and for the purpose specified.

In testimony whereof I affix my signature in presence of two witnesses.

JOSHUA B. DETWEILER.
